INVENTOR:
Anna M. Pachmayer
By Atty:
Frederic M. Keeney.

UNITED STATES PATENT OFFICE.

ANNA M. PACHMAYR, OF LOS ANGELES, CALIFORNIA.

TOOTHBRUSH.

Application filed December 23, 1921. Serial No. 524,462.

To all whom it may concern:

Be it known that I, ANNA M. PACHMAYR, a citizen of the United States, residing in the city and county of Los Angeles and 5 State of California, have invented a new and useful Improvement in Toothbrushes, of which the following is a specification.

This invention has relation to new and useful improvements in tooth-brushes, and 10 the specific object of this invention is the provision of a brush of this character having a handle which may be used in either a parallel or angular position relative to the part carrying the bristles, thus adapting the 15 brush to a more handy position for the operator.

In cleaning the teeth, an up and down motion of the brush serves to more efficiently remove all foreign matter therefrom. To 20 facilitate the manipulation of the brush with this motion, I have provided a brush with the handle angularly disposed relative thereto, and capable of being reversed so that the brush may be used similar in manner 25 to the ordinary brush. With the handle in angular position to the bristle carrying portion, my improved brush may be employed with greater facility for cleaning the inner side of the teeth, and is equally 30 handy for cleaning the rear as well as the front teeth.

To this end, the invention consists in certain novel features of construction, combination and arrangement of parts, as will 35 be hereinafter more fully described and claimed.

For a complete understanding of my invention, reference is to be had to the accompanying drawings, in which:

40 Figure 1 is a side view of my improved tooth-brush, in which the handle is reversible to either parallel or angular position relative to the bristle carrying part. Fig. 2 is a fragmentary view of the same. Fig. 45 3 is a fragmentary view showing the detail construction of the brush shown in Figs. 1 and 2.

Referring to the drawings, my improved tooth-brush consists of a non-breakable

handle 26, of twisted wire. The metallic 50 handle 26, is reversible relative to the bristle-carrying member 27, but is not detachable. Member 27 is provided with an integral and angular boss 28, and a stud 29 having a beveled head 30. The handle 26, has flattened spring ends 31 and 32, engaging, respectively, with the beveled head 30, and the beveled boss 28. In reversing the handle, the inner spring end 32, will be pressed out of engagement with boss 28, 55 and, when in fully reversed position, will re-engage with the angular and beveled boss 28, thereby holding the member 27 firmly 60 in position.

From the foregoing description and 65 drawings, it may be seen that I have provided a simple and efficient tooth-brush, in which the handle may be reversed in position relative to the brush, which greatly facilitates the manipulation of the brush 70 vertically and in an effective manner.

What is claimed is:

1. A brush embodying a bristle-supporting plate and bristles thereon, an angular boss on the back of the plate and integral 75 therewith, a stud mounted on the boss, a beveled and circular head on the stud, a handle, and flattened and spring ends on the handle, engaging respectively, with the angular boss and with the beveled head 80 on the stud.

2. A brush embodying a bristle-supporting plate and bristles thereon, an angular and beveled boss on the back of the plate and integral therewith, a stud projecting 85 centrally from the angular boss, a beveled head on the stud, a handle for the plate, and flattened and spring ends on the handle and engaging respectively, with the angular and beveled boss and with the beveled head, 90 said boss serving to maintain the handle in alignment with the plate in one position, and in angular position to the plate in the opposite position.

In testimony whereof, I hereunto affix my 95 signature.

ANNA M. PACHMAYR.
